UNITED STATES PATENT OFFICE.

HARRY R. DECKER, OF HOUSTON, TEXAS.

OIL AND WATER WELL STRAINER.

No. 880,635.

Specification of Letters Patent.

Patented March 3, 1908.

Application filed November 17, 1906. Serial No. 287,885.

To all whom it may concern:

Be it known that I, HARRY R. DECKER, a citizen of the United States, residing at Houston, in the county of Harris and State 5 of Texas, have invented certain new and useful Improvements in Oil and Water Well Strainers, of which the following is a specification.

My invention relates to strainers for use in 10 oil and water wells to separate the fluid from the sand that usually contains it.

My invention is an improvement on strainers of the wire-wound class and consists in the wrapping of a perforated pipe 15 with a wire having projections extending from the inside, and below the narrow edge of the wire. This wire is wrapped around the pipe with the projections resting upon the pipe, the body of the wire being above 20 and free from contact with the pipe, the circulating space between and underneath the wire only being restricted in any manner whatever where the projections referred to come in contact with the pipe. These projections can be so made by being extended 25 outward from the wire as well as downward that a base is formed for the wire of greater width than its upper and exposed edge. The wire so made affords three distinct advantages: First, the wire is braced and securely held in position against its next winding and can not shift and change the spacing between the wires. Second, the width of the base determines the space of the slits between the 35 wires, making the operation of spacing, when winding the wire on the pipe, exact and accurate. Third, the wire being above and free from contact with the pipe—except where the projections occur—a maximum 40 of freedom is allowed the fluid after entrance into the strainer through the slits between the wires, to flow uninterruptedly in any direction until it reaches the nearest perforation in the pipe. Another advantage in my 45 improved wire is that by making the sides of these projections triangular in shape, and the apex just below the top of the wire the inlet space of the slits is entirely unrestricted, and bracing, spacing and free flow for the fluid 50 in every direction is provided without in any way reducing the effective area of strainer surface.

By reason of my improved construction in elevating the wire above the pipe and allowing it to rest on projections, it is possible— 55 and is contemplated in my improvement—

to make this wire with straight sides, using a flat wire rectangular in cross-section as shown in the drawings, and still have a much greater circulating space than is provided with the present type of wires which hug the pipe. 60 By this method of construction a great advantage would be derived in providing a thickness of wire at the point where the fluid enters the strainer and which under certain 65 conditions is subjected to considerable wear and tear. Such wear and tear when oil is found in a stratum containing gas under heavy pressure is serious and very destructive to the present type of strainers, and frequently wears away and cuts the edge of the wires forming the slits, enlarging the 70 space between the windings and making the strainer ineffective because of unequal width of slits and sand being admitted through same. 75

My invention will be described in detail hereinafter and illustrated in the accompanying drawings in which—

Figure 1 is a view of fragment of a strainer tube partly in section showing my improved 80 winding wire in position, Fig. 2 a side view of one form of wire that may be used with my improved strainer. Fig. 3, a cross-sectional view of the wire shown in Fig. 2, Fig. 4, a side view of another form of wire that may be 85 used, and Fig. 5, a cross-sectional view of the wire shown in Fig. 4.

In the drawings similar reference characters indicate corresponding parts throughout the several views.

1 represents the strainer pipe or tube having its lower end closed and provided with holes 2 adjacent thereto. The tube 1 is wrapped with a wire 3. My invention consists in the improvement of the construction 95 of this wire of which two forms are shown in the drawings. In Figs. 2 and 3 a wire is shown that is triangular in cross-section, while in Figs. 4 and 5 the wire is flat.

In Figs. 2 and 3 the wire is designated by 100 the reference character 4. 5 represents flat projections on one side of the wire that are flush with one edge of its outer surface 6, while 7 represents triangular projections on the other side of the wire that have their 105 outer surface beyond the plane of the other edge of the outer surface 6. The apex 8 of the triangular projection 7 is, however, below the level of the surface 6 so that when the wire is in position the projections 5 and 7 110 engaging one another space the coils of the wire apart so as to admit the oil or water there-

- between but to exclude the sand containing said liquid. When in position the apex 8 of the triangular projection 7 does not extend into the slit between the coils of the wire so that the entrance of the oil or water is not impeded in the least, while the triangular projections form an effective brace to prevent the coils of wire upsetting should obstructions be encountered in the well tube.
- 10 The projections 5 and 7 extend below the inner edge 9 of the wire 4 to form legs as shown at 10 to hold the edge of the wire away from the pipe 1 so that the fluid entering between the coils of the wire may flow directly to one 15 of the holes 2 in the pipe.
- As shown in the drawings the legs 10 are formed on each side of the wire and are arranged in pairs spaced apart so that the liquid flowing between the coils may freely 20 flow therebetween, this structure providing a substantially unobstructed chamber between the tube 1 and the winding wire so that the liquid may pass without obstruction to the nearest hole 2 in the tube.
- 25 In the form shown in Figs. 4 and 5 the wire instead of being of triangular shape is flat and indicated by the character 11 with projections 12 extending from its inner surface having one side flush with the edge of the wire 30 while the other side of the projections project beyond the other edge of the wire and is in the shape of a triangle as shown at 13 having its apex 14 below the outer surface of the wire. The bases of the projections 12 are cut 35 out as shown at 15 so that the fluid that may flow through the spaces between the coils of the wire when in position may flow to the holes 2 without being impeded.
- Having thus described my invention what 40 I claim is—
1. In a strainer; a perforated pipe, wire wrapped thereon, and means integral with said wire to space it from the pipe and form a chamber between the wire and pipe, substantially as shown and described.
  2. In a strainer, a pipe having holes therein, and wire wrapped thereon having legs to space the wire from the pipe and form a chamber between the wire and pipe, substantially as shown and described.
  3. In a strainer, a pipe having holes therein, and wire wrapped thereon having projections extending from one of its sides, said
- projections being extended beyond the inner edge of the wire to form legs to space the wire from said pipe, substantially as shown and described.
4. In a strainer, a pipe having holes therein, and wire wrapped thereon having projections extending below its base, one of the edges of said projections being triangular in shape and extending beyond the plane of the corresponding edge of the wire, substantially as shown and described.
5. In a strainer, a pipe having holes therein, and wire wrapped thereon having projections extending below its base, one of the edges of said projections being triangular in shape and extending beyond the plane of the corresponding edge of the wire, the apex of the triangular projection being below the surface of the wire, substantially as shown and described.
6. In a strainer, a pipe having holes therein, and wire wrapped thereon rectangular in cross-section and having projections extending below its base, substantially as shown and described.
7. In a strainer, a pipe having holes therein, and wire wrapped thereon rectangular in cross-section and having projections extending beyond its sides, said projections being extended beyond the inner edge of the wire to form legs to space the wire from said pipe, substantially as shown and described.
8. In a strainer, a pipe having holes therein, and flat wire wrapped thereon having projections extending below its base, one of the edges of said projections being triangular in shape and extending beyond the plane of the corresponding edge of the wire, substantially as shown and described.
9. In a strainer, a pipe having holes therein, and wire wrapped thereon having projections extending below its base, to form a chamber between the wire and pipe, and projections on one side of the wire extended beyond its plane to space the adjacent coils of wire from one another, substantially as shown and described.

In testimony whereof I hereto affix my signature in the presence of two witnesses.

HARRY R. DECKER.
